L. OTTINGER

MEANS FOR ATTACHING HANDLES TO DOOR LATCHES

Filed June 26, 1920

Inventor
Leon Ottlinger,
By his Attorney
C. P. Goepel

UNITED STATES PATENT OFFICE.

LEON OTTINGER, OF NEW YORK, N. Y.

MEANS FOR ATTACHING HANDLES TO DOOR LATCHES.

Application filed June 26, 1920. Serial No. 391,887.

To all whom it may concern:

Be it known that I, LEON OTTINGER, a citizen of the United States, and a resident of the city of New York, in the county and State of New York, have invented certain new and useful Improvements in Means for Attaching Handles to Door Latches, of which the following is a description.

This invention relates to an improved means for attaching handles to door latches, and more particularly to the latches or locks of automobile doors.

It is the primary object of the present invention to provide a means for the attachment of such latch handles which will permit of the complete finishing of the door with the latch applied thereto and the upholstery on the inner side of the door covering the latch casing without necessitating the detachment or lifting of the upholstery for the purpose of properly attaching the handle to the latch. To this end I have devised a means for the attachment of the handle, wherein the handle is initially inserted through an opening in the door from the outer side thereof, and positioned for operative connection to a part of the latch mechanism, and an opening is then cut in the upholstery on the inner side of the door to admit of the application of means whereby the handle will be rigidly and permanently attached to the latch part.

In one embodiment of a practical means for carrying out the purposes of the present invention I have provided simple and efficient means for effecting an adjustable and separable operative connection between the shank of the operating handle and the part of the latch mechanism which actuates the latch bolt. This feature of the invention, which I shall herein describe in detail, serves to insure the proper fitting and connection of the handle with the latch regardless of mechanical irregularities in the construction of the parts, as may be incident to the mode of manufacture thereof, so that the proper functioning of the parts will be assured.

In general it is the aim and object of the present improvement to provide a means for the attachment of handles to door latches or locks which will enable such attachment to be made with great ease and facility and economy of time.

With the above and other objects in view, the invention consists in the several steps of the improved method to be subsequently set forth in detail, and in the form, construction and relative arrangement of the several parts included in the illustrated embodiment of the means for effecting the attachment, as will also be hereinafter more fully explained, and said means then subsequently incorporated in the subjoined claims.

In the drawings, wherein I have illustrated one adaptation of the invention, and wherein similar reference characters designate corresponding parts throughout the several views:

Figure 1 is a horizontal sectional view through a part of an automobile door, to which the latch is attached, showing the upholstery in place on the inner side of the door.

Figure 2 is a similar view showing means for positioning the shank of the operating handle for connection to the latch part, and the means for forming the opening in the upholstery of the door.

Figure 3 is a detail elevation of the pilot member for the cutting tool.

Figure 4 is a horizontal sectional view similar to Figure 1, showing the means for effecting the final permanent attachment of the handle to the latch.

Figure 5 is a fragmentary elevation of the inner side of the door with the handle attached thereto.

Figure 6 is a detail fragmentary longitudinal section of the handle shank.

Figure 7 is an end elevation thereof.

Figure 8 is a detail elevation of the expansion screw for expanding the end of the handle shank.

Figure 9 is an enlarged sectional view more clearly illustrating the means for attaching the handle to the roll back of the latch mechanism, and,

Figure 10 is a similar view illustrating another application of the handle shank to the roll back.

Referring in detail to the drawings, the latch, generally indicated at 20, is secured in a recess 21, formed in the inner side of the door frame 22. As herein illustrated, the latch mechanism includes a roll back 23 for the operation of the latch bolt. This

roll back is provided with a square or rectangular passage or opening 24 therethrough, which is gradually tapered or of decreasing area from one end to the other 5 of the roll back. The roll back is mounted for oscillatory rotating movement in the opposite side plates of the latch casing.

An opening 25 is bored through the door frame 22 from the outer side thereof to the 10 recess 21, said opening being of circular form and in coaxial relation with the passage 24 through the roll back 23, but of appreciably greater diameter than said opening. The wall of this opening 25 at its 15 outer end, is screw-threaded, as at 26, and a bearing bushing 27 is screwed therein, said bushing having a flange 28 at its outer end to engage against the sheet metal covering or sheath 29 on the rear face of the 20 door. The bushing is further provided in its end with an annular recess 30.

Preferably the opening 25 through the door frame is produced in accordance with the disclosure in my co-pending application 25 for patent on means for forming handle holes in doors or the like, Serial No. 391,886, filed June 26, 1920, and is particularly desirable in cases of this kind where great 30 exactness is an essential requisite to the proper fitting of the latch handle, as the invention disclosed in said application will operate to produce an opening through the door frame in exact concentric and axial alignment with the passage through the 35 roll back.

After the latch has been applied to the door frame, and the opening 25 provided therein, the upholstery material 31 is applied to the inner face of the door, and is 40 secured thereto by means of suitable tacks indicated at 32. This upholstery material completely covers the latch casing, and extends over the end of the roll back 23.

The handle for the operation of the latch 45 mechanism includes a flanged hub portion 33, an angularly extending lever or other equivalent manipulating portion 34, and a rectangular shank portion 35 secured to the hub 33 or integrally formed therewith, 50 and extending in coaxial relation with said hub.

In the manufacture of such door latches the roll backs are produced from cast metal, the opening or passage 24 being formed 55 therethrough by means of a core, and in the withdrawal of this core the opening is slightly tapered from one end to the other thereof, as shown. Inasmuch as this core is extracted or withdrawn from the roll back, sometimes in one direction, and sometimes in the opposite direction, the relation of the opening through the roll back to the opposite sides of the latch casing is not always the same. Consequently it frequently 60 happens that a defective connection between

the handle and the roll back results when the parts are assembled, so that the latch does not properly function.

In Figure 9 of the drawings I have illustrated the application of the handle to the roll back when the larger end of the opening therethrough faces towards the inner side of the door, and in Figure 10 I have shown such application when the larger end of the opening faces outwardly. The 70 handle shank 35 is of slightly less cross sectional area than the opening through the roll back, so that said shank may be readily inserted within said opening. The facility 75 with which the shank of the handle may be positioned with respect to the roll back is furthered by the fact that the bushing 27 is in exact axial alignment with the opening 25 through the door and the opening 24 through the roll back. The handle shank 80 is of such length that when fully inserted it will project slightly beyond the end face of the roll back. The end portion of the shank 35 extending through the opening in the roll back is longitudinally split at diametrically opposite points, as shown at 85 35', said splits extending radially with respect to the axial center of said shank. This split end portion of the shank 35' is formed with an axial bore 36, which extends slightly inward of the inner ends of the split shank portions, and is screw-threaded. The outer end of this bore 36 is formed with a flaring or conical smooth 90 surface to provide a seat 37 for the tapering or conical portion 39 of the expansion screw 38. At the larger end of the conical portion 39 of said screw a cylindrical portion 40 is provided, having a head or flange 41. A diametrically extending groove 42 95 is formed in the end face of this head for the application of a screw driver thereto.

The handle is operatively attached to the latch mechanism in the following manner: Assuming that the door has been completed or finished, with the latch applied thereto, as shown in Figure 1, I first temporarily attach a pilot member 54 to the split end of the handle shank 35. This member 54 is formed at one end with a sharply pointed 110 prong, and is provided at its other end with a split shank 55. This shank or base portion is adapted to be forced into the bore 36 in the end of the handle shank, so as to become detachably wedged therein. The shank 35 with the pilot member attached, is now inserted through the opening 25 in the door frame, the hub portion 33 fitting within the bushing 27, while the split end of the shank enters the passage 24 in the roll back. Of course, as the handle shank is moved into 120 said passage 24, an opening will be cut through the upholstery material 31 by the pointed end of the pilot member 54, and said member will protrude beyond the inner face 125 130

of the door. This penetration of the pilot member through the upholstery material I have indicated at 43^a in Figure 2 of the drawings. There is now applied a rotary cutting tool 45 upon the protruding pilot member 54, said cutting member including a cylinder body having a shank 44 at one end and a cup-shaped cutting flange 46 at its opposite end. The body of the cutter is 10 provided with an axially extending bore 47 to receive the projecting end of the pilot member 54. Thus it will be apparent that this member serves to accurately center the cutting tool, so that its axis of rotation is 15 in exact axial relation with the handle shank 35. The tool 45 is now operated to cut a circular disc from the upholstery material 31, thereby producing the opening 43 therein, which is concentrically related to the 20 roll back. The pilot member 54 may now be readily withdrawn and detached from connection with the handle shank 35 without first requiring the removal of the handle.

The next and final step in the method of 25 assemblage of the handle to the roll back is to effect the permanent operative connection between the parts. For this purpose I first assemble the expansion screw 38 in connection with a face plate or disc 48, which is of 30 greater diameter than the opening 43 through the upholstery, said face plate being centrally provided with the opening 49, in which the cylindrical portion 40 of the screw is loosely engaged. The plate 48 is 35 further formed with the annular recess 50 to receive the head 41 of the screw. The face plate 48 is placed in position over the opening 43 in the upholstery with the expansion screw 38 engaged through the opening 49 in said plate. This screw enters the bore 36 in the split end of the shank 35, and, 40 as the screw is threaded inwardly into said bore, the conical portion 39 of said screw is brought into engagement upon the seating surface 37, whereby the split end portions of the shank 35 are expanded in radial directions, and are urged into tight 45 frictional gripping engagement with the walls of the passage 24 through the roll back.

It will be noted that each split portion 50 of the shank has angularly related exterior faces, which are caused to frictionally contact throughout their area, with the opposed angular surfaces at the corners of the opening 24 in the roll back. Accordingly it 55 will be appreciated that all possibility of relative axial movement between the handle shank and the roll back will be precluded, 60 so that the proper operation of the roll back and the functioning of the latch mechanism is assured. When this final gripping action takes place, the flange or head 41 on the screw is loosely engaged in the annular recess 50 of the plate 48, but does not bind 65 against said plate, so that the screw is perfectly free to turn or rotate with the handle shank with relation to the face plate. This face plate provides a complete closure for the opening 43 formed in the upholstery, 70 and does not detract from the artistic appearance of the upholstery or finish on the inner side of the door.

As clearly shown in Figure 9 of the drawings, when the split end of the handle shank is expanded, as just explained, said shank will substantially conform precisely with the tapering opening or passage through the roll back, when the larger end of said opening faces towards the inner side of the door, 75 thus resulting in a wedge connection between the parts. However, as above noted, the shank 35 is of such length that in its applied position it projects slightly beyond the end face of the roll back, so that when the roll back is disposed in the position seen in Figure 10, with the smaller end of the opening therethrough facing towards the inner side of the door, the protrusion of the extremity of the handle shank beyond said end 80 of the opening will still insure a positive and reliable connection of the split end of the shank with the roll back, as the split end of the shank, when expanded, is of greater area than the smaller end of the opening 24. 85

From the foregoing description, considered in connection with the accompanying drawings, the means which I have devised for the attachment of handles to latches or locks will be fully understood. Not only 90 may the attachment be effected in a more facile manner, and with considerably less labor than heretofore, but the attachment will be mechanically perfect, since it admits of an accurately adjusted connection between the handle shank and the roll back, 95 so that such connection need be neither too tight nor too loose. Accordingly the proper functioning of the parts under all conditions of service will be obtained, and in particular, the roll back may, at all times, 100 freely turn upon its bearings without binding in the slightest degree. I have found this means for the attachment of the handle to be particularly desirable in that type of 105 latch used upon automobile doors, as disclosed, for instance, in any prior U. S. Patent No. 1,312,199, patented Aug. 5, 1919, in which the roll back is normally held by 110 means of a spring, the proper functioning of which would be retarded, if not rendered impossible by a binding action upon the roll back or the handle shank.

In the foregoing description and the accompanying drawings I have illustrated one 115 desirable and practical embodiment of the invention, but it will, nevertheless, be understood that both the method and means for the attachment of the handle may be successfully adapted and applied in other alter- 120

125

130

native embodiments, and I, therefore, reserve the privilege of adopting all such changes and modifications as may be fairly embodied within the spirit and scope of the 5 invention as claimed.

I claim:

1. In combination with a door, a latch carried by the door, a roll-back forming a part 10 of the latch, a spindle fitting through the roll-back, upholstery on the face of the door and against the latch, a plate fitting against the upholstery, and means for securing the plate against the upholstery and for rigidly fixing the spindle within the roll-back.
2. In combination with a door, a latch carried by said door having a rollback provided with an opening, an operating spindle for said rollback having an expandible end 20 portion fitted through said opening, upholstery extending over one face of the door and having an opening therein at one end of said rollback, a member for expanding the end of the spindle against the wall of 25 the opening in said rollback, and a closure for the opening in said upholstery rotatably engaged by said member.
3. The combination with a door, a latch casing secured in the door and having a roll-back therein with an opening therethrough, upholstery secured to the inner side of said door and having an opening therein at one end of the roll-back, a washer fitting over 30 the opening in the upholstery, a spindle projecting through the door and having a split end entering the opening in said roll-back, and a member for entering said split end of the spindle and acting to expand the same against the wall of the opening in said roll-back, said member also acting to hold said washer in place.
4. In combination with a door, a latch casing secured in the door and having a roll-back therein with a tapered opening, upholstery secured to the inner side of said door and having an opening therein at one end of the roll-back, means to cover said opening, said door having an opening extending in alinement with the opening in said roll-back, a bushing in the outer side of the opening in said door, an operating spindle journaled in said bushing and having a socket-

ed and split end engaging loosely through the tapering opening in said roll-back, the inner portion of said socketed end of the 55 spindle being interiorly threaded and the outer portion thereof having a conical wall, and a bolt threaded into the threads in said socket and having a conical outer portion adapted to expand the split part of said 60 spindle, said bolt having a head to bear against said means for covering the opening in the upholstery.

5. In combination with a door, a latch carried by said door having a rollback provided with an opening, an operating spindle having an end portion fitted through the opening in the rollback, upholstery secured from one face of the door and having an opening therein at one end of said rollback, 70 a closure for said opening, and a common means for rigidly securing said spindle in the opening of the rollback and for retaining said closure in its applied position.

6. The combination with a door having a 75 latch applied to one side thereof, the latch including a rotatable roll back provided with an axially tapering opening, and the door being provided with an opening in alignment with the opening in the roll-back 80 and having upholstery material applied to the above-mentioned side of the door and covering the latch casing, said material having an opening therein to expose one end of the roll back, of an operating handle for the latch mechanism, having a shank adapted to be inserted and positioned in the opening in the roll back, a bearing for said handle, secured in one end of the opening in the door, the end of said shank being longitudinally split, and provided with a threaded bore, a washer plate adapted to be engaged over the opening in the upholstery, and an expansion screw adapted to be threaded into the bore of the handle shank 95 to expand the split end thereof, and frictionally engage the same with the walls of the opening through the roll back, said screw loosely coacting with said washer to close the opening in the upholstery. 100

In testimony that I claim the foregoing as my invention, I have signed my name hereunder.

LEON OTTINGER.
